UNITED STATES PATENT OFFICE

ABRAHAM BOTKIN, OF YONKERS, NEW YORK

DESIGN FOR A FINGER RING OR SIMILAR ARTICLE

Application filed June 10, 1930. Serial No. 36,011. Term of patent 14 years.

To all whom it may concern:

Be it known that ABRAHAM BOTKIN, citizen of the United States, and resident of Yonkers, N. Y., in the county of Westchester and State of New York, has invented a new, original, and ornamental Design for Finger Ring or Similar Article, of which the following is a specification, reference being had to the accompanying drawing, forming part thereof, in which—

Fig. 1 is a top plan view of a finger ring embodying my new design;

Fig. 2 is a front elevational view thereof; and

Fig. 3 is a cross-sectional view, taken on line 3—3 of Fig. 2.

I claim:

The ornamental design for a finger ring or similar article, substantially as shown.

Dated, June 5, 1930.

ABRAHAM BOTKIN.
